UNITED STATES PATENT OFFICE.

MARTIN MACDERMOTT AND WILLIAM GLOVER, OF LONDON, ENGLAND.

ROCK-DRILLING MACHINE.

SPECIFICATION forming part of Letters Patent No. 320,371, dated June 16, 1885.

Application filed March 15, 1884. (No model.) Patented in England September 17, 1881, No. 4,008, and July 5, 1883, No. 3,334; in Germany January 9, 1884, No. 28,197, and in Austria-Hungary December 16, 1884, No. 39,594 and No. 59,188.

To all whom it may concern:

Be it known that we, MARTIN MACDERMOTT and WILLIAM GLOVER, subjects of the Queen of Great Britain, and residing at London, England, have invented new and useful Improvements in Rock-Perforating Machines, (for which we have obtained patents in Great Britain, No. 4,008, dated 17th September, 1881, and No. 3,334, dated 5th July, 1883; in Germany 5 by Patent No. 28,197, dated January 9, 1884, and in Austria-Hungary by Patent No. 39,594 and No. 59,188, dated 16th December, 1884,) of which the following is a specification.

This invention has for its object improvements in machines in which hand-labor is employed for boring rocks by percussion.

The annexed drawings show a rock-perforating machine constructed in accordance with the invention.

Figure 1, Sheet 1, is a side elevation. Fig. 2, Sheet 1, is a front elevation, partly in section. Figs. 3 and 4, Sheet 2, represent a front and side view, respectively, of the nut-box and its attachments on an enlarged scale. Fig. 5 represents a partial horizontal section of the same. Fig. 6 is a side elevation, on a larger scale, of a modified arrangement for effecting the rotation of the drill-bar. Fig. 7 is a front elevation of the same, and Figs. 8 and 9 details, showing 20 a front view and an edge view, respectively, on an enlarged scale, of the ratchet mechanism.

The frame *a* of the machine contains a tubular carrier, *b*, to which a reciprocating movement is imparted, as hereinafter described. The carrier has at its end a roller-plate, *b'*, carrying two rollers, and discontinuous cam-projections are provided on the face of a rotating disk or plate, which operate against the roller, drawing the carrier upward toward the 35 axis of the plate-cam, and then releasing it for the blow and admitting of the return-motion being effected by a spring, *f*. Usually it is convenient to employ two of these plate-cams, one on either side of the carrier.

In the drawings, *d* is the axis to which the handles are applied, *e e* are the plate-cams, and *e' e'* the cam-projections upon them. The axis of the plate-cams is furnished with fly-wheels. The carrier *b* has a disk, *z*, upon it, against 40 which the hereinbefore-described coiled spring *f*, contained in a spring-box, *a'*, forming part

of the frame *a*, abuts. The carrier also at its inner end (or that farthest from the plate-cams) is enlarged into a box, *b''*, in which a nut, *h*, is contained, and a tube, *i*, with a screw-thread upon it, passes through the carrier *b* from end to end and through the nut *h*. 55

Within the tubular screw *i* the bar *j* is carried in such a manner that it is free only to turn on its axis. It is formed at one end with 60 a socket, *j'*, in which the tool *j''* is clamped; also, beyond the screw *i*, in the opposite direction, the drill bar *j* has a collar, *j''*, fixed upon it. The drill-bar partakes of the reciprocating motion which the tubular screw *i* receives through the nut *h* in the box *b''* at the end of the carrier. At each reciprocation the end or edge of the tool carried by the drill-bar strikes upon the rock. In the latter part of the stroke a trigger, *k*, mounted upon the carrier upon the side of the nut-box *b''*, comes into contact with a stationary tappet, *l*, upon the frame *a*. The trigger then gives movement to a ring, *m*, through a link, *m'*, in the direction of the arrow shown at the lower part of Fig. 4, 70 75 the ring *m* carrying a pawl, *n*, engaging with a ring of ratchet teeth, *o*, upon the nut *h*. A spring, *s*, connected with the pawl-ring, brings this ring back in the direction of the upper arrow during the return-stroke of the machine 80 and turns the nut, thereby advancing the hollow screw *i*, the bar *j*, and the drill *j''*. The amount of the advance depends upon the distance the drill penetrated at the last impact, for the trigger is operated only in the 85 latter part of the stroke, and if the stroke is brought to an early conclusion by the resistance of the rock the trigger is moved but little or not at all. The screw *i* is prevented from turning with the nut *h* by a feather or tooth, 90 *b''*, in the disk *z*, against which the spring *f* abuts. It is capable of being retracted out of the groove in the screw for a purpose to be explained further on. In the interval between the strokes which the drill-bar *j* is thus caused 95 to make against the face of the rock it is necessary that the drill-bar should be turned partly round, so that the edge of the drill or tool *j''* may not always strike in the same place. This is effected by means of a beveled pinion, *p*, upon the head of the bar *j* engaging with another similar pinion, *q*, upon the same axis,

q, as that of a ratchet-wheel, *q*². The edge of the cam-plate *e* is itself made into a cam at *e*^x, as the drawings show, and it operates to move a bell-crank lever, *r*, driving by means of a 5 pawl, *s*^x, this ratchet *q*², and beveled gearing. This pawl *s*^x may be held to its engagement with the ratchet *q*² by any ordinary means—as, for instance, by a box, or strap, or spring, *y*, or any simple equivalent device. When it is 10 required to disengage the pawl *s*^x from the ratchet, the pawl is pulled down so that the flat part *z*' of said pawl (see Fig. 6) is caused to bear upon the spring *y*, whereby the pawl is kept disengaged. This operation of turning 15 the drill partly round at each stroke is, however, effected in a more simple manner by means of the arrangement shown in elevation at Fig. 5, Sheet 2, of the accompanying drawings, and which is the arrangement we prefer employing. This arrangement consists of a bar, *t*, 20 which is made spiral at one end and is attached to the roller-plate *b*', thereby participating in the reciprocating motion of the same. The spiral end of this bar runs through a corresponding spiral hole in the pinion *v*, and thereby the pinion *v* is turned at each motion. The pinion *v*, gearing with a pinion, *v*', which is cast 25 on the boss of the beveled pinion *p*, causes the bar *j* to turn also at each motion. To prevent 30 the bar *t* from turning while imparting motion to the pinion *v*, a ratchet-wheel, *w*, and pawl are fixed at the lower end of the bar, allowing it to turn only on the return-stroke. When 35 the hole in the rock has been drilled to the full depth required, the drill-bar *j* has to be run back out of the hole, and to effect this conveniently the drill-bar is connected with the screw *i*, through which it passes, by means 40 of a catch, *x*', provided for this purpose, engaging in a notch in the socket *j*', (which socket is a continuous part of the drill-bar,) 45

and the screw *i* and drill-bar *j* will thereby be firmly locked so as to rotate together. At the same time the feather or tooth *b*², which prevents the screw turning, is withdrawn by means of its button or head *x*, and the drill-bar can be turned by means of a handle applied at its upper end, and the tool can be thus withdrawn rapidly. 50

Having thus described the nature of our said invention, what we claim is—

1. In a rock-perforating machine, in combination with the drill-carrier *b* and with the drill-bar *j*, the rotating plate-cam *e*, having on its face a disconnected series of cam-projections, *e*', serving to lift the carrier, and having also a series of edge cams, *e*^x, serving to turn the drill-bar, all substantially as shown and described. 55

2. As a means for partially rotating the drill-bar, the combination of the lifting cam-plate and its series of peripheral cams *e*^x, the bell-crank lever *r*, actuated thereby, the ratchet *q*², upon a shaft, the pawl *s*^x, engaging therewith and provided with a flat part, *z*', spring *y*, adapted to bear against said flat part when the pawl is disengaged, and the gears *q*' and *p*, these parts co-operating together, substantially as set forth. 60

3. In combination the following elements, 70 namely: the drill-holder and mechanism for rotating it, the feed-screw connected with the drill-holder, a nut engaging said screw and mechanism for rotating it, a spline engaging said screw, and a device for withdrawing it 75 from engagement, and a catch on the feed-screw engaging a notch in the drill-holder.

M. MACDERMOTT.
W. GLOVER.
